UNITED STATES PATENT OFFICE.

WALTER W. CERVANTES, OF NEW YORK, N. Y., ASSIGNOR OF ELEVEN-TWENTIETHS TO FREDERICK A. WARE AND JOHN M. DEEMER, OF NEW YORK, N. Y.

EYEGLASSES.

SPECIFICATION forming part of Letters Patent No. 782,545, dated February 14, 1905.

Application filed March 13, 1903. Serial No. 147,556.

To all whom it may concern:

Be it known that I, WALTER W. CERVANTES, a citizen of the United States, and a resident of New York, county of New York, and State of New York, have invented certain new and useful Improvements in Eyeglasses, of which the following is a specification; reference being had to the accompanying drawings, forming a part thereof, in which similar characters of reference indicate corresponding parts.

This invention relates to improvements in eyeglasses or spectacles of the frameless variety, the object thereof being to provide an efficient means for coupling the lenses to the spring-bow and nose-clips in eyeglasses and nose-bridge in spectacles without the aid of frames for surrounding the lenses, and in such a secure manner as to obviate liability of having them become accidentally loosened from their fastenings, whereby they are constantly maintained in rigid and properly-extended position.

The invention comprises a bifurcated hanger and a semi-elliptical spring, so arranged as to keep the hanger in secure and proper relative arrangement with the lens, as will be herein-after fully described, and specifically set forth in the annexed claim.

In the accompanying drawings, forming part of this specification, I have illustrated my invention as applied to eyeglasses.

Figure 1 is a face view of one-half of a pair of eyeglasses having parts broken away in sectional elevation, and Fig. 2 is a sectional plan view taken on the line $\alpha\alpha$ of Fig. 1.

In the practice of my invention the hanger or coupler A, employed for connecting the lens to the nose-clip and spring-bow embodies a post a , an elongated base embodying the longitudinally-extended parts a' , bifurcated clamp a' , and the grooved head a'' , all formed integral and of soft malleable metal and being of design and construction similar to the ordinary couplers, excepting that the extended curved arms for contact with the lens edge do not form a part thereof. Instead of these arms I employ a semi-elliptical spring B, composed of highly-tempered metal of a charac-

ter considerably harder than that employed in the construction of the other parts of the coupler, whereby the ends b of said spring, which have the functions of the ordinary soft-metal arms, can not be accidentally bent away from the edge of the lens after the parts are connected. The said spring B is of a width equal to the distance between the arms of the clamp a' , and its ends b are tapered and rounded at the point, whereby no lateral extensions are presented, and it is secured to the under part of the post a by means of the screw 1, which has its head countersunk into the spring, whereby a clear space is provided between the edge of the lens and the spring-body part, to allow play of the spring. This detachable arrangement allows of ready removal of the spring from the coupler, while at the same time the device embodies an operative whole, susceptible of use in connection with lenses and bridge connections of ordinary construction.

The head a'' of the coupler connects the nose-clip C and the spring-bow D, which are held in place by means of the screw E in the customary manner, and the clamp a' embraces the lens F and is secured thereto by means of the screw 2, which passes through the opening f in the lens F, and the two arms of the clamp a being threaded into one of them.

In the operation and use of the invention the clamp a' is forced against the tension of the spring B over the lens F until its oppositely-located openings are concentric with the opening f of the lens and held in this position by the operative until the screw 2 is driven securely into place, and owing to the fact that the opening f is slightly larger in diameter than the screw the adjustment of said screw can be readily effected without liability of injuring the lens. Then upon releasing pressure from the spring the ends thereof, by reason of their tendency to regain normal shape, will force the lens outwardly, so that the wall of its opening is forced into contact with one side of the screw, thus securely clamping the lens in place, but at the same time allowing for expansion and contraction of said lens relatively with the

metal parts without liability of having it crack, as lenses frequently do when clamped too tight.

By use of this invention the lens is not only maintained in rigid position, but the screw 2, owing to the pressure constantly exerted thereon, is prevented from accidentally turning to allow lateral spreading of the arms of the clamp a' . Thus the relative secure engagement of the parts is constantly maintained.

I do not confine myself to the specific details of construction nor design of the parts as herein shown and described, as it is obvious that under the scope of my invention I am entitled to slight structural variations. For instance, when the invention is applied as a coupler between the bridge and lenses of a pair of spectacles the head end of the post would be slightly modified in shape.

Having now described my invention, what I claim as new, and desire to secure by Letters Patent, is—

In a coupler for connecting a lens to the bridge parts of eyeglasses or spectacles, the

combination with the metallic post having a screw-threaded recess in the bottom thereof, and embodying the base, head and bifurcated clamp, each arm of said clamp having an opening therethrough, of the detachable spring, 3, which is semi-elliptical in side elevation, and has a countersunk central opening and tapering ends rounded at their points, and a screw detachably fastening the spring to the post and having its head countersunk in the said opening of the spring, said spring composed of tempered hard metal and of a width equal to the distance between the arms of the said clamp, whereby the parts comprising the coupler are normally attached, but readily detachable, substantially as shown and described.

In testimony that I claim the foregoing as my invention I have signed my name, in presence of two witnesses, this 6th day of February, 1903.

WALTER W. CERVANTES.
